UNITED STATES PATENT OFFICE

2,596,233

PRESSURE VESSEL

Donald B. Gardner, Oak Park, Ill., assignor to
 Bell & Gossett Company, Morton Grove, Ill., a
 corporation of Illinois

Application April 6, 1946, Serial No. 660,226

1 Claim. (Cl. 220—66)

1

My invention relates to pressure vessels and more particularly to that type which comprises a shell closed at one or both ends by a separate head.

In a characteristic arrangement involving a vessel of the above type, the head is bolted to the shell which necessarily requires a flanging of the head and the end of the shell, or the securing of a separate ring to the shell which functions as an attaching flange, and bolt openings in the flanges. Such a construction is expensive to manufacture and uniformity of contact between the shell and head is difficult to obtain, particularly where the vessel takes the form of a heat exchanger having tubes supported in a tube sheet at the head end and it is required to attach a multi-chambered head to the shell in such a way that a substantial interior seal is effected between the head and shell and the partitions in the head act as stays for the tube sheet.

It is therefore the principal object of my invention to provide a tube sheet equipped, pressure vessel having a partitioned head closing an end thereof in which the head is welded to the shell and the shrinkage of the weld forces the partitions in the head tightly against the tube sheet.

These and further objects of the invention will be set forth in the following specification, reference being had to the accompanying drawing, and the novel means by which said objects are effectuated will be definitely pointed out in the claim.

In the drawing:

Fig. 1 is an elevation, partly in section, of a typical heat exchanger embodying the invention.

Fig. 2 is an enlarged sectional elevation of the right end of the exchanger, as viewed in Fig. 1, or as taken along the line 2—2 in Fig. 3.

Fig. 3 is an enlarged section along the line 3—3 in Fig. 1.

Figs. 4 and 5 are sectional details showing successive steps in closing one end of the exchanger shell.

Referring to the drawing, the pressure vessel which, as a matter of disclosure is arranged as a heat exchanger, comprises a shell 10 which at one end may be closed by a head 11 secured thereto in any conventional manner, as by welding. A tube sheet 12 is mounted in the opposite end of the shell 10 and closing and shaped for mating relation with this end is a dished head 13. The interior of the head 13 is divided by a diametral partition 14, spaced partitions 15 and 16 extending laterally with respect to and from one side of the partition 14, and a partition 17 ex-

2

tending from the opposite side of the partition 14 at an elevation between the partitions 15 and 16. These partitions define with the head 13 and the tube sheet 12 a plurality of chambers 18, 19, 20, 21 and 22, the chamber 18 being connected to a source of supply by an inlet nipple 23 and the chamber 22 discharging through an outlet nipple 24, although the direction of flow may be reversed.

Fluid entering the chamber 18 makes several longitudinal traverses of the shell through banks of tubes generally indicated by the numeral 25 in Fig. 3. These tubes are arranged in a manner well known in the heat exchanger art and so that the fluid first enters the tubes through the chamber 18 and then flows successively through the chambers 19, 20, 21 and 22, traverses of the shell 10 being effected between the chambers 18 and 19, 19 and 20, 20 and 21, and 21 and 22. The other exchanging fluid may be introduced into the shell 10 through a connection 26 for flow over the tubes 25 and discharged through a connection 27.

So far as described, the exchanger does not differ in any substantial respect from those of existing types. The invention consists in the mode of attachment of the head 13 to the shell 10 and the important results flowing therefrom. In assembling this end of the exchanger, the tube sheet 12 is first secured to the shell by a circumferential weld 28 (see Fig. 4) so that a portion of the sheet extends beyond the end of the shell to provide an annular shoulder 29. The head 13 is then telescoped over the shoulder 29 to abut the exposed edges of the partitions 14, 15, 16 and 17 against the tube sheet 12 and sufficient clearance is left between the weld 28 and the facing edge of the head to enable the application of a circumferential weld 30 that tightly secures the head to the tube sheet and shell.

The tube sheet serves as a backing ring for the welds and the normal shrinkage of the weld which attaches the head draws those edges of the partitions 14, 15, 16 and 17 which face the tube sheet tighter into contact therewith. This arrangement not only hermetically seals the end of the shell but provides a working tightness between the tube sheet and the partitions dividing the interior of the head so that, for most practical purposes, the chambers 18, 19, 20, 21 and 22 are sealed from each other. To facilitate the obtaining of this result, the exposed edges of the partitions 14, 15, 16 and 17 are faced smooth to insure intimate contact with the tube sheet. If a higher degree of seal is desired in these localities, suitable gaskets may be interposed between

the tube sheet 12 and the abutting edges of the partitions 14, 15, 16 and 17.

In addition to dividing the interior of the head 13 into a plurality of chambers, the partitions 14, 15, 16 and 17 by reason of their abutting relation to the tube sheet 12 function as stays for and support this sheet against pressure within the shell.

I claim:

In a pressure vessel, the combination of a shell, 10 a wall fitting within and extending transversely of the shell at one end thereof, a portion of the wall projecting beyond the shell to provide a shoulder, a dished head fitting over the shoulder with its edge face spaced from the adjacent end 15 of the shell to thereby define a channel extending around the exposed periphery of the wall, and welding material in the channel for secur-

ing the shell, wall and head together, the head being interiorly divided by partitions which abut and tightly contact the wall.

DONALD B. GARDNER.
